ROTARY HAMMER TOOL

Ludvik Rasch, Oslo, Norway

Application March 22, 1935, Serial No. 12,506
In Norway May 13, 1933

5 Claims. (CL. 125—33)

This invention relates to a rotary hammer, wherein a hammer body during the rotation of a carrying member is caused by centrifugal force to strike against a striking member or an anvil.

5 During its motion in the carrying member the hammer body is checked by an air cushion in a main compartment arranged in the carrying member. The cross sectional area of the main compartment is substantially filled by the hammer body during its motion. The main compartment communicates with an auxiliary compartment which serves to regulate the checking action.

At any revolution of the carrying member the hammer is flung out from the main compartment and strikes against the anvil. During further rotation of the carrying member the hammer again jumps into the main compartment, wherein its velocity is braked or checked by an air cushion in the bottom of the main compartment, the hammer being at the correct time pressed ahead again and gives off a new blow. Thus at each revolution of the carrying member one blow is effected.

20 25 In hammers of this kind an exact regulation of the braking effect is necessary, which depends upon the number of revolutions of the carrying member. The hammer body should not strike against the compartment bottom, because in such case it might jump too early out from the compartment and would then not strike the anvil at the correct time.

Such a bottom blow is prevented, if no auxiliary compartment is present. However, then the tool 30 operates too hardly, because the air cushion at the inner main compartment portion operates already from the moment, at which the hammer body enters the compartment. The operation is the harder the further back the hammer body 35 is moved into the compartment. For this reason the auxiliary compartment is used, whereby the size of the air cushion can never be reduced beyond the capacity of the auxiliary compartment. The operation of the air cushion is therefore softer, but frequently it is still too hard, so 40 that the hammer body jumps out too early.

Therefore, a pressure valve must be arranged which like a safety valve prevents the pressure in the auxiliary compartment from increasing beyond a certain limit by letting out the superfluous air quantity. However, from this follows again an increased air vacuum during the motion of the hammer body out from the main compartment. Besides, during this motion it should not 45 be too much braked, because then the intensity

of the blow would be correspondingly reduced. Consequently, also a suction valve must be arranged in order to let in air. Thus two valves were necessary in the carrying member, whereby the construction is complicated and the operation 5 unsafe. In addition, the escape of air through the pressure valve causes a considerable loss in power. Further, the carrying member and the hammer body gradually become highly heated.

I have now discovered that the reason for the 10 said difficulties resides essentially in this that the main compartment and the auxiliary compartment have together a too small capacity. If this is increased, it may certainly be effected by increasing the auxiliary compartment. But 15 thereby their braking effect during the last part of the inward motion of the hammer body will be too small, so that the hammer body is inclined to strike the bottom of the main compartment.

According to the present invention the said 20 difficulties are avoided by having the connection between main and auxiliary compartments controlled by the hammer body proper.

In the previous constructions both compartments were in open communication with one another, but according to the present invention this communication can be interrupted by the hammer body proper, when it has moved far enough into the main compartment and before 30 it has reached on to the bottom thereof. Only at the moment wherein the communication is interrupted, an efficient air cushion arises in the bottom to stop the hammer body very rapidly close to its bottom position. In this arrangement the capacity of the auxiliary compartment 35 may be considerably increased without a bottom blow be risked. The hammer body moves nevertheless always far into the compartment, and air need not be let out. The air pressure behind 40 the hammer body will not, as before, increase evenly to the highest exhaust pressure, but it increases at first evenly and comparatively slowly until the said communication is interrupted.

Then the pressure increases very rapidly without any exhaust. During the hammer motion out from the compartment the pressure decreases correspondingly in the invert succession. The braking is soft and only at the last moment hard.

50 An embodiment of the invention is illustrated in the drawings. Fig. 1 shows an elevation of the hammer partly in longitudinal section. Fig. 2 is a sectional view substantially on the line II—II of Fig. 1, the carrying member and the hammer 55

body being however shown in section on the line IIa—IIa.

The hammer body 1 is as usually turnable about a pivot 2 in the carrying member 3. The pivot is located eccentrically to the rotating axis 4 of the carrying member, and the hammer body turns during its return motion, after the blow against the anvil 5, into the main compartment 6. However, it should never strike its bottom 7. Nevertheless the hammer body should be caused to move most possibly close to the bottom. The carrying member 3 is maintained in rotation as usually in direction of the arrow by gear wheels 8, 9 from the motor shaft 10. The motor is not shown. It is enclosed in a housing 11 between the hammer housing 12 and the handle 13. The carrying member 3 is journaled in the housing 12 by means of ball bearings 14.

Now, according to my invention the auxiliary compartment 15 is separated from the main compartment 6 and communicates therewith through channels 16, 17, 18. The channel 18 ends in the lateral wall of the main compartment at some distance from the bottom face 7 and is closed as soon as the hammer body moves past it. As soon as the hammer body during its return rotation about the pivot 2 has reached the uttermost part 19 of the main compartment, the braking commences by the air contained in both compartments 6 and 15. The braking effect increases softly and uniformly until the hammer body has closed the channel 18. Then the air quantity behind the hammer body has been suddenly limited to a small air cushion within the compartment 6. Simultaneously the braking effect increases very rapidly. The hammer body is stopped and again pressed out from the compartment, at first with a high force, whereby it is rapidly accelerated and then, as soon as the channel 18 has been opened, with a less force. In this manner an advantageous pressure curve is obtained.

Usually the air has no noticeable time to flow out from the compartments. But should this take place, a vacuum is created in the compartments. Such a vacuum also arises always in starting the tool. In order not to make the starting difficult, a suction valve may according to my invention be arranged in the carrying member. The valve is provided with a lateral channel 20 enclosing a valve ball 21 with spring load 22. The channel 20 continues behind the valve seat into a lateral channel 23 ending in the compartment bottom 7.

Provisions may also be taken to prevent the hammer body 1 from moving completely to the bottom of the compartment 6, when the hammer is to be stopped. For this purpose a side nose 24 is provided on a pin 25 movable radially in the carrying member 3, or other suitable means may be used. The pin is pressed by a spring 26 into the shown position, wherein the nose 24 projects into one corner of the compartment 6 so as to stop the inward motion of the hammer body, before it reaches the bottom 7. When the hammer is started, the nose remains in this position, until

the carrying member 3 has obtained a certain minimum number of revolutions. Then the centrifugal force pulls the pin 25 outwards opposite the action of the spring 26, so that the nose 24 now is outside the compartment 6 and allows the hammer body to move further in towards the bottom 7.

The channel 16 ends in the auxiliary compartment 15 at or close to the point which is located most distant from the rotating axis 4. The oil which might have entered the compartment 15 will then always be removed by the centrifugal force and pass out into the main compartment 6 with the expanded air.

I claim:

1. A rotary hammer tool, comprising a rotary carrying member, a stationary surrounding casing, an anvil movably arranged therein, a hammer body turnably mounted eccentrically in said member, a main compartment so arranged in 20 the carrying member and so shaped that at one rotating direction the hammer body moves into the compartment in nearly tight proximity to its side walls opposed by an air cushion in the bottom part of the compartment and at the opposite 25 direction it moves, owing to centrifugal force, out from the compartment and produces a blow upon the anvil, a separate auxiliary compartment arranged in the carrying member, a communication passing from the auxiliary compartment to an 30 opening arranged in the main compartment wall at some distance from its bottom, so that the hammer body during its motion in the carrying member controls the connection between both compartments. 35

2. A rotary hammer tool according to claim 1, wherein the communication between both compartments ends in the auxiliary compartment at a point located most distant from the rotating axis of the carrying member. 40

3. A rotary hammer tool according to claim 1, wherein a loaded air suction valve is arranged in the carrying member and means connecting the suction side of the valve with the atmosphere and the opposite side with the bottom of the main 45 compartment.

4. A rotary hammer tool according to claim 1, wherein a pin is arranged movably substantially radially in the carrying member, a spring tending to press said pin inwardly, a nose so arranged on 50 the pin that under the spring tension it is urged to project into the main compartment at some distance from its bottom.

5. A rotary hammer tool according to claim 1, wherein a pin is arranged movably substantially 55 radially in the carrying member, a spring tending to press said pin inwardly, a nose so arranged on the pin that under the spring tension it is urged to project into the main compartment at some distance from its bottom, the spring being so sized 60 that the pin is retracted from the compartment by a predominant centrifugal force, as soon as the rotating velocity of the carrying member increases beyond a certain limit.
